UNITED STATES PATENT OFFICE

152,293

DESIGN FOR A HANGING FLOWER BASKET

Jack Shaw, Brooklyn, N. Y.

Application March 19, 1947, Serial No. 137,742

Term of patent 3½ years

(Cl. D35—2)

To all whom it may concern:

Be it known that I, Jack Shaw, a citizen of the United States, residing at Brooklyn, in the county of Kings and State of New York, have invented a new, original, and ornamental Design for a Hanging Flower Basket, of which the following is a specification, reference being had to the accompanying drawings, forming part thereof.

Fig. 1 is a top plan view of a hanging flower basket, showing my new design.

Fig. 2 is a front elevational view; and

Fig. 3 is a side elevational view of Fig. 2, illustrated with a small portion broken away to better illustrate my design.

I claim:

The ornamental design for a hanging flower basket, as shown.

JACK SHAW.
